UNITED STATES PATENT OFFICE

133,641

DESIGN FOR A SWITCH CONTACT

Vernon L. High, Freeport, Ill., assignor to Micro
Switch Corporation, Freeport, Ill., a corpora-
tion of Illinois

Application April 8, 1942, Serial No. 106,493

Term of patent 14 years

To all whom it may concern:

Be it known that I, Vernon L. High, a citizen of the United States, residing at Freeport, in the county of Stephenson and State of Illinois, have invented a new, original, and ornamental Design for a Switch Contact, of which the following is a specification, reference being had to the accompanying drawing, forming part thereof.

In the drawing:

Figure 1 is a perspective view of a switch con-

tact embodying my new design, the side not shown being plain, and

Figure 2 is a fragmentary perspective view on an enlarged scale of the surface ornamentation thereof.

I claim:

The ornamental design for a switch contact, substantially as shown and described.

VERNON L. HIGH.
